UNITED STATES PATENT OFFICE.

FRANK H. QUADE, JR., OF FRESNO, CALIFORNIA.

INKING MECHANISM.

1,192,454.

Specification of Letters Patent. Patented July 25, 1916.

Original application filed August 2, 1913, Serial No. 782,729. Divided and this application filed January 27, 1915. Serial No. 4,777.

To all whom it may concern:

Be it known that I, FRANK H. QUADE, Jr., a citizen of the United States, residing at Fresno, in the county of Fresno and State 5 of California, have invented certain new and useful Improvements in Inking Mechanism, of which the following is a specification.

This invention relates to machines for printing letters, circulars and the like, by 10 which the heading of the letter may be printed with ordinary printing ink of any desired color, the body of the letter through an inked ribbon, and the signature from an electrotype or the like so inked as to give 15 the effect of having been written. A type of such machine is disclosed in Letters-Patent, No. 1,041,314, granted to J. F. Mahlstedt, October 15th, 1912, and the present invention relates especially to the inking mechanism or the means employed to transfer ink from a source of supply to the electrotype and to the type faces from which 20 the letter head is to be printed.

This application is a division of an application filed by me August 2nd, 1913, Serial 25 No. 782,729.

The improvements constituting the present invention will be hereinafter first fully described and then more particularly pointed 30 out in the claims following the description.

In the accompanying drawings, which fully illustrate my present invention:—Figure 1 is a longitudinal vertical section of so much of a printing machine as is necessary to impart a proper understanding of 35 the general arrangement and the particular features forming the subject-matter of my improvements; Fig. 2 is an enlarged perspective view of the ink trough with its supports and the parts immediately co-acting therewith; Fig. 3 is a longitudinal section 40 through the ink trough showing the parts in operative position; Fig. 4 is a similar view showing the parts adjusted to prevent 45 the feeding of ink; Fig. 5 is a detail view of a latch employed in connection with the ductor roll; Fig. 6 is a detail view of a rack bar which is provided on one side of the type bed; Fig. 7 is a detail perspective view of a 50 portion of the ink-trough support; Fig. 8 is a perspective view of the mechanism for rotating the ink table; Fig. 9 is a detail bottom plan view of a portion of the mechanism shown in Fig. 8.

The main frame 1 of the machine may be 55 of any convenient or preferred construction, and in the upper portion of the said main frame is mounted a type bed 2 which is reciprocated longitudinally of the main frame through a lever 3 fulcrumed upon the main 60 frame and connected with the type bed by a link 4. Motion is imparted to the lever 3 through a crank shaft 5 and a pitman 6 which may be actuated through any convenient mechanism. Upon the upper portion of 65 the main frame is mounted an impression roller 7 working in connection with sheet feeding devices, indicated generally at 8, and with a delivery mechanism, indicated generally at 9, by which the printed sheets are 70 removed from the machine. A throw-off lever 10 is also mounted upon the upper portion of the frame, and this lever controls the devices for feeding the ribbon and means for stopping the operation of the machine 75 when desired.

The type bed 2 as it reciprocates longitudinally of the main frame carries the type under the transfer rollers 11 by which the ink is transferred to the type faces, and my 80 present improvements relate more particularly to the means whereby ink is supplied to these transfer rollers. Said transfer rollers are preferably provided in pairs, as shown in Fig. 1, one pair being mounted 85 upon the main frame near each end of the same, and each pair of the rollers applies ink to the faces of a portion of the type carried by the type bed.

To the type bed and projecting beyond 90 each end thereof I secure brackets 12, each of which is adapted to support an ink table 13 and means for periodically imparting a rotary movement to said table. The ink table at each end of the type bed is a duplicate of the table at the other end of the type bed, and a description of one with its operating mechanism will suffice for both. For convenience and clearness in the illustration, only one inking table and its operating 95 mechanism is shown. It will be observed upon reference to Fig. 1 that the brackets 12 vary slightly in form at their inner ends. This variance in form is merely to accommodate the arrangements of the ribbon-carrying mechanism at the opposite ends of the type bed and has no function in the operation 100 of the machine.

The bracket 12 is preferably a U-shaped frame or bar secured rigidly to the type bed and provided at its outer end with an up-standing hollow post or boss. The ink table 5 is provided with a depending stem adapted to fit within the said boss or post and capable of rotation therein, as will be readily understood. A cylindrical stud is fitted in the lower end of the post or boss, and the upper 10 end of this stud bears directly against the lower end of the stem so as to aid in supporting said stem, while a pin, indicated in dotted lines in Fig. 8, is disposed eccentrically upon the upper end of said stud and 15 enters a correspondingly located socket in the lower end of the stem whereby the rotary movement imparted to the stud will be imparted directly to the stem and the ink table thereby given the desired movement. A set-screw 18 is mounted in the side of the post and enters an annular groove 19 in the stud whereby to swivel said stud within the post, as will be readily understood. The stud will 20 thus be prevented from dropping from the post and, at the same time, will be free to rotate therein.

The ink to be fed to the type is placed in ink troughs 38, one of which is provided at each end of the machine, as shown in Fig. 1, 30 and each ink trough is so located as to be within the vertical plane of the ink table co-acting therewith. The rear ink trough is supported by a cross bar 39 which is secured rigidly to end brackets 40 secured to the 35 main frame of the machine at the corners of the same, as will be readily understood. The front ink trough is carried by a similar cross bar 39' to which brackets 40' are secured, but the brackets 40' are shorter than the 40 brackets 40, as shown in Fig. 7, and the bar 39' projects beyond the brackets and is provided with openings, as also shown in Fig. 7, through which screws or bolts are passed to secure the bar to the standards which 45 carry the delivery roller.

Journalized in and extending between the upper corners of each pair of the brackets 40 or 40' is a shaft 41 which has the fountain roll 42 preferably integral therewith at a 50 point about midway its length. Immediately adjacent the ends of the fountain roll, the diameter of the shaft 41 is reduced, as shown at 43, to permit the side walls 44 of the ink trough to engage the shaft and fit 55 close to the ends of the said roll so as to prevent leakage of ink around the ends of the roll. The ends of the said side walls are notched, as indicated most clearly in Figs. 3 and 4, so as to more readily engage the 60 shaft, and the edges of the notches, which are at an angle to the bottom of the trough, should fit fairly snug on the shaft so as to make a tight fit at point of contact but a slight movement of the trough will leave an 65 opening between the trough and the roll.

The action is thus positive when more ink is needed.

The ink trough is preferably constructed of a sheet metal plate having its ends turned up in triangular form to provide the side 70 walls 44 and having one side edge turned down, as shown at 45, to present a depending flange or lip to facilitate the adjustment of the trough. The lower edge of the trough, as shown in Fig. 4, may bear against the 75 fountain roll 42 and, when the parts are in this position, no ink will be fed from the trough. The trough rests upon the central portion of the cross bar 39 in an oblique position, as shown, and to the said cross bar 80 I fit the end of a screw 46 which extends outwardly and upwardly through the depending flange 45 of the trough. An adjusting nut 47 is mounted upon the said screw and bears against the outer side of the said flange, 85 while a spring 48 is carried by the cross bar 39 and has one end bearing against the inner face of said flange 45 so as to act thereon in opposition to the nut 47. It will be readily understood that, by turning the nut in one 90 direction, the trough will be forced inwardly and downwardly against the tension of the said spring and, by turning the nut in the other direction, the spring will be free to expand and thus move the trough upwardly 95 and outwardly. In this manner, the flow of the ink may be readily controlled so as to be cut off entirely or fed at any desired speed or in any desired quantity to the ink table.

Below the ink trough a shaft 49, angular in cross section, extends between the brackets 40 and has its ends journaled in said brackets. At intermediate points of the said shaft, I secure the arms 50 which project laterally from the said shaft to points 105 below the shaft 41 and are adapted to carry the ductor roll 51. The length of the ductor roll 51 is preferably the same as the length of the fountain roll 42, but less than the distance between the supporting arms 50 so as 110 to facilitate the fitting of the said roll between said arms. The arms are constructed with openings near their free ends adapted to receive the elongated pintles or trunnions 52 extending from the ends of the ductor 115 roll, and it will be readily understood that, by inserting one of said pintles through the opening intended to receive the same and sliding said pintle beyond the point at which it is to be supported, the pintle at the other 120 end of the roll may be brought into alignment with its bearing and the roll and both pintles then again moved longitudinally so as to engage the last-mentioned pintle in its bearing.

One of the pintles is preferably provided with an annular groove, and a latch 53 is pivotally mounted upon the arm 50 which receives said pintle, said latch being provided with a notch 54 to engage said groove 130

and thereby retain the pintle and the ductor roll in its operative position. The inner end of this latch is preferably beveled, as shown at 55, to bear against the faces of the angular shaft or rod 49 and be thereby limited in both its upward and its downward movements, and a spring 56 is coiled around the pivot 57 of the latch and has one end bearing against the lower edge of the arm 50 and its other end engaged in a notch 58 in the latch so as to hold the latch in engagement with the adjacent pintle 52. The free end of the latch is preferably bent laterally to provide a handle or thumb piece 59 for convenience in releasing the same when it is necessary to repair or clean the machine. The fountain roll 42 is preferably constructed of some hard material, while the ductor roll 51 is preferably made of composition.

A floating weight 60 is provided in the trough to bear upon the ink and force the same toward the rolls. This floating weight may conveniently be in the form of a cylinder extending between the side walls of the trough, but as it should not roll downwardly and thereby feed the ink too rapidly to the rolls, I provide a rod 61 which is rigid with the weight and extends upwardly therefrom so as to engage over the upper edge of the trough. This rod, by its engagement with the upper edge of the trough, will prevent rotation of the weight and also serves as a handle to permit the removal of the weight from the trough or its insertion therein.

At one end of the fountain roll shaft 41, I secure a ratchet wheel 62 which is engaged by a pawl 63 carried by a trip lever 64. The said trip lever 64 is fitted upon the adjacent end of the angular shaft 49, and a spring 65 extending between the lever and the pawl 63 serves to hold the said pawl in engagement with the ratchet wheel 62. A lock nut 66 is fitted upon the pivot 67 of the said pawl, and the said pivot also carries a roller 68 which is adapted to ride upon a track 69 provided on one side of a rack bar 70 which is formed upon or secured to one side of the type bed. The track 69 has one end beveled, as shown at 71, so that it will readily engage under the roller 68 and thereby cause an upward movement of the lever 64 and pawl 63.

It will be readily understood that a track 69 is provided near each end of the type bed, and that the inclined face of the said track extends in opposite directions at the opposite ends of the type bed. This arrangement is indicated at 71 and 72 in Fig. 6 of the drawings.

When the lever 64 is given a vertical movement under the action of the track 69, as just described, the ratchet wheel 62 will be partially rotated and a partial rotation thereby given the fountain roll shaft 41 and the fountain roll 42. At the same time, the

angular shaft 49 will be partly rotated inasmuch as it must follow the movement of the lever 64 which is fast thereon, and the arms 50 will be thereby swung upwardly so as to carry the ductor roll against the fountain roll to receive ink therefrom. The parts will remain in this raised position as long as the roller 68 is in engagement with the track 69, and the ductor roll will thereby receive a full supply of ink from the fountain roll. When the roller 68 reaches the inclined end of the track upon the reverse movement of the type bed, the parts will be returned to their lower position and the ductor roll will bear upon the surface of the ink table which will then take ink from the roll. On the next movement of the type bed, the transfer rolls 11 will receive ink from the ink table and in turn will apply the ink to the type faces.

A spring, indicated at 73, is coiled around the end of the shaft 49 and has its ends secured respectively to the lever 64 and the adjacent bracket 40 so that, as the inclined end 71 or 72 of the track 69 passes from under the roller 68, the parts will be positively moved to their lower position so that the ductor roll will be in position to bear upon the ink table. At the opposite end of the said shaft 49 I secure a stop arm 74 which projects outwardly and upwardly from the said shaft and is equipped at its upper end with a stop 75 adapted to bear upon the cross bar 39. This stop is preferably in the form of a segmental disk pivoted to the upper end of the arm 74 and held in frictional engagement therewith by a spring 76 coiled around its pivot between the said arm and the head of the pivot. The parts are so proportioned and relatively arranged that, when the straight edge of the segmental disk is presented to the cross bar, the shaft 49 may oscillate and the ductor roll drop to the ink table, but when the curved or arcuate edge of the disk is presented to the cross bar, the stop arm 74 will be held away from the cross bar and the shaft 49 held in such position that the ductor roll will be maintained raised against the fountain roll. This mechanism, it will be readily understood, permits the operator to easily control the feed of ink and retard the flow when the supply upon the ink table should tend to become too copious or thick for successful printing.

In Figs. 8 and 9, I have shown the mechanism for imparting rotary movement to the ink table. The post 78 on the frame 12 receives the stem 79 of the ink table, and the said stem is engaged with and receives motion from the stud 80 which is swiveled in the post 78 in the manner previously described. The ratchet wheel 81 is fast to the lower portion of the stud 80, and below the said ratchet wheel a swinging plate 82 is

pivots mounted upon the stud, a washer 83 being fitted upon the stud below the said plate 82 to retain the same in place. The operating lever 84 is disposed transversely to the frame 12 and is pivoted to one side of the same, as indicated at 85, a link 86, having its opposite ends pivoted respectively to the said lever and the plate 82, serving to connect the lever and the plate 6 and to transmit the motion of the lever to the plate, as will be readily understood. The pivot which connects the link to the lever is in the form of a post 87 to which is secured one end of a spring 88 having its opposite end secured to the frame 12 at a point near the post 78. A pawl 89 is pivoted upon the swinging plate 82 and is held in engagement with the ratchet wheel 81 by a spring 90 which is coiled around the pivot 91 of the pawl and has its opposite ends engaging the pawl and a pin 92 on the plate, as clearly shown in Fig. 8. To prevent retrograde movement of the ratchet wheel, a holding pawl or dog 93 is pivoted upon the frame 12 and is held to the ratchet wheel by a spring 94 coiled around the pivot 95 of the pawl and having its opposite ends respectively engaging the pawl and the holding pin 96 on the frame. A post 97 is carried 10 by the main frame of the machine in the path of movement of the lever 84. The post is formed at its lower end with a U-shaped stirrup which is pivoted within the U-shaped bracket 98 secured rigidly to the main frame. 15 The lower ends of the U-shaped stirrup are convex so as to permit the post to swing readily upon its pivot but the outer side of the stirrup normally bears against the outer end or cross plate of the bracket 98 so that 20 the post will be in an upright position. A spring 99 is coiled around the pivot and has its opposite ends secured respectively to the stirrup and to the bracket 98. 25 When the type bed moves inwardly in the 45 operation of the machine, the transverse lever 84 will ride against the post 97 and cause the same to swing down into the housing or supporting bracket 98 within which it is pivoted. When the lever 84 has cleared 50 the post 97, said post will return to its upright position under the influence of the spring 99, and on the return movement of the type bed the outer edge of the lever 84 will engage the said post. As the post cannot swing outwardly, the lever will be forced 55 to swing inwardly and toward one side thereby exerting a pull upon the plate 82 through the link 86 and against the tension of the spring 88 whereby the pawl 89 will 60 be caused to ride over the ratchet wheel 81. As soon as the lever 84 clears the upright post 97, the spring 88 will contract and thereby swing the lever 84 to its normal position and the link 86 will then exert a pushing force upon the plate 82 so that the pawl 65

89 engaging the ratchet wheel 81 will rotate said ratchet wheel and through the intermediate parts will effect a partial rotation of the ink table. With the mechanism just described, the ink table may be given a quarter 70 turn at each successive operation.

From the foregoing description, taken in connection with the accompanying drawings, it will be readily seen that I have provided exceedingly simple and compact mechanism by which the ink may be effectually transferred from the ink fountain to the type faces, and that the ink will be distributed evenly over the ink table and, consequently, applied evenly to all the type 75 faces. The flow of the ink may be easily regulated and no waste of the ink will be permitted. The mechanism for rotating the ink table is all below the table, and there are no notches in the edge of the table or 80 openings through the table through which the ink might leak and be wasted. The ink table may be readily removed from its bearing without disturbing the operating mechanism and repairs may be easily made when 85 desired. The ink will be taken from the ink trough or fountain only as it is needed, and should the ink be supplied too fast, its flow may be retarded or cut off until all the ink upon the ink table has been used. The 90 stoppage or retardation of the flow from the ink trough, moreover, will not necessitate any stoppage or reduction in speed of the operation of the printing mechanism. 95

Having thus described the invention, 100 what is claimed as new is:—

1. In a printing machine, the combination of a main frame, a reciprocating type bed mounted thereon, a rotatable ink table carried by the end of the type bed, a ratchet wheel locked to said ink table and concentric therewith, a turning plate pivotally mounted concentric with the ratchet wheel, a pawl on said plate engaging the ratchet wheel, a lever carried by the type bed, a link connecting said lever with the turning plate, and means for vibrating said lever. 105

2. In a printing machine, the combination of a main frame, a reciprocating type bed mounted thereon, a rotatable ink table carried by the end of the type bed, a ratchet wheel locked to said ink table concentric therewith, a turning plate pivotally mounted concentric with the ratchet wheel, a pawl on said turning plate engaging the 110 ratchet wheel, a transverse lever carried by the type bed, a link connecting said lever with the turning plate, a yieldable post on the main frame in the path of said lever, and a spring acting on the free end of the 115 lever at the side thereof more remote from the post. 120

3. In a printing machine, the combination of a reciprocating type bed, an ink table carried by the type bed, an ink trough, a 130

fountain roll arranged to take ink from the trough, a ductor roll adapted to engage the fountain roll and the ink table, a pivoted rod below the trough, arms projecting from 5 said rod and supporting the ductor roll, a latch pivoted on one of said arms and adapted to lock the ductor roll therein, one end of said latch being cut obliquely and adapted to limit the downward movement of the 10 latch by engaging with one side of the pivoted rod and to limit the upward movement of the latch by engaging the adjacent side of the rod when raised, a spring adapted to normally hold said latch in a lowered position, 15 means for propelling the fountain roll while the machine is printing, and means to swing said rod about its pivot.

4. In a printing machine, the combination of a reciprocating type bed, an ink 20 table carried by the type bed, an ink trough, a fountain roll arranged to take ink from the ink trough, a weight suspended in the ink trough, means to prevent rotation of said weight, means for propelling the fountain roll while the machine is printing, and 25

means for transferring ink from the fountain roll to the ink table.

5. In a printing machine, the combination of a reciprocating type bed, an ink table carried thereby, a stationary support arranged above said type bed, an ink trough on said support, a fountain roll arranged to take ink from said trough, a rod pivoted in the stationary support, a ductor roll carried by said rod, means actuated by the type bed 30 to move the ductor roll to and from the fountain roll, a stop arm carried by the pivoted rod, and projecting upwardly therefrom adjacent the support, and a segmental disk carried by the free end of said stop 35 arm and adapted to engage the support to permit or prevent the raising and lowering of the ductor roll.

In testimony whereof I affix my signature in presence of two witnesses.
